UNITED STATES PATENT OFFICE

146,551

DESIGN FOR A FOOD DISPENSER

Wilbur Henry Adams, Millcreek Township,
Erie County, Pa.

Application November 13, 1945, Serial No. 123,667

Term of patent 3½ years

(Cl. D44—24)

To all whom it may concern:

Be it known that I, Wilbur Henry Adams, a citizen of the United States, residing at township of Millcreek, in the county of Erie and State of Pennsylvania, have invented a new, original, and ornamental Design for a Food Dispenser, of which the following is a specification, reference being had to the accompanying drawing, forming part thereof.

Fig. 1 is a top plan view of a food dispenser showing my new design;

Fig. 2 is a side elevational view;

Fig. 3 is an end elevational view; and

Fig. 4 is a top perspective view thereof.

Characteristic features of my design reside in the portions shown by means of full lines in the drawing.

I claim:

The ornamental design for a food dispenser, as shown and described.

WILBUR HENRY ADAMS.
